A. E. YACCARINE.
ERASER HOLDER.

APPLICATION FILED SEPT. 14, 1912. RENEWED FEB. 28, 1914.

1,113,527.

Patented Oct. 13, 1914.

UNITED STATES PATENT OFFICE.

ANTHONY E. YACCARINE, OF BROOKLYN, NEW YORK.

ERASER-HOLDER.

1,113,527.

Specification of Letters Patent.

Patented Oct. 13, 1914.

Application filed September 14, 1912, Serial No. 720,348. Renewed February 28, 1914. Serial No. 821,834.

To all whom it may concern:

Be it known that I, ANTHONY E. YACCARINE, a citizen of the United States, residing in Brooklyn, in the county of Kings and 5 State of New York, have invented certain new and useful Improvements in Eraser-Holders, of which the following is a specification.

This invention has for its object to provide 10 a form of eraser attachment that can be applied to various objects so that the eraser is always convenient for use, yet will not be lost.

The invention is especially designed for 15 use in connection with a typewriter, to be clamped to a convenient part of the machine and grasped by the hand and used on the work in the machine, and as soon as released the eraser will return to its place on the machine 20 automatically to be always ready for future use.

A further object of the invention is to provide a device in the nature of a frame or casing containing winding means to wind 25 up a cord that is attached by its free end to a typewriter desk or other place, and which frame carries an eraser on an extension of the frame so as to form a convenient handle or grasping means to firmly hold the 30 eraser for use, and which further will serve to present the entire edge of a circular eraser as generally used.

A further object is to provide such a device with means for readily applying the 35 usual form of circular eraser, whereby when it has been worn away it can be readily removed and a fresh one substituted.

In the accompanying drawing, showing one embodiment of my invention, Figure 1 40 shows the device in side elevation; Fig. 2 is a longitudinal section; Fig. 3 shows the outer shell of the casing; Fig. 4 is a section on the line 4—4 of Fig. 3; Fig. 5 is a side elevation of the device with one of the plates 45 and the outer shell removed; Fig. 6 is a section on the line 6—6 of Fig. 3; Fig. 7 shows the sheave; Fig. 8 shows one of the frame plates; and, Fig. 9 shows the other frame.

The device, as set forth, comprises a frame 50 that is formed by two plates of flat sheet metal of elongated form, one plate 12 extending in a plane having the body portion 13 provided with an extension 14. At the center of the head is a stud 15 on which ro-

tates a sheave 16, shown separately in Fig. 7. This sheave is somewhat dish-shaped having a chambered portion 17 in which is placed a volute spring 18 whose inner end extends into a slot 19 in the stud 15 to lock this end of the spring, which is wound 60 around the stud as indicated in Fig. 5; and has its outer end secured to the sheave 16, so that when the sheave is turned to wind up the spring, upon release the spring will unwind and rotate the sheave on the stud. 65 The periphery of the sheave is provided with a channel 20 that receives a suitable cord 21 which is wound in this channel in the opposite direction to the spring, so that by pulling the cord the sheave will rotate 70 to wind up the spring, and when the cord is released the spring rotating the sheave will wind the cord back on its periphery.

An annular shell 51 is provided having 75 rib portions 22 and 23 on its faces that are broken away at the part 24, and the inner diameter of the rib portion is such that it will receive the head 13 of the plate 12, with the sheave member projecting into the open space 25 of the shell, the head beyond the 80 shell engaging the face portions 26 of the casing where it is suitably secured. An aperture 27 is provided in the opposite part of the shell from the part 24 through which the cord 21 passes, and the edges of this 85 aperture are suitably curved to prevent undue friction on the cord. A second plate member 28, similar in shape to plate 12, is provided that has its head portion 29 placed on the shell 51 on the opposite face from 90 that engaged by the plate 12, as indicated in Fig. 2, and these two plates are secured together through the shell, thereby forming a casing that incloses the sheave 16 with its attached spring and cord; the head 29 being provided with a circular hole for receiving the stud 15 that is suitably secured thereto, as by riveting. The extension 30 of the plate 29 is deflected at 31 so as to bring the part 30 into engagement with the extension 14 of the other plate, as shown in Fig. 2, and these extensions are suitably secured together, thereby forming a strong and rigid 95 extension of the casing. These extension plates are provided with a stud 32 secured at a hole 33 therein on the inner side or in alinement with the sheave in the casing, and this stud is of a size to pass through the 100

105

hole provided in the usual form of circular eraser E, as shown in Figs. 1 and 2. When the eraser is placed on this stud it will be in alinement with the shell and its contents, and suitable means are provided for securing the eraser on this stud so that it can be removed and another substituted when desired.

In the construction shown a lever 35 is hinged to the plate 28 by a pin 36, and the lever has a slotted portion 37 that when swung will engage the slotted head 38 of the stud 32, and thereby serve to secure the eraser on the stud; it being understood that the eraser is rotatable on the stud to present all portions of its margins for use. Suitable means are provided for securing the lever in closed position, the slotted portion of the end of the lever may have a tight engagement with the slotted head, or the lever may be provided with an extension at its inner end containing a lug 40 that, when the lever is closed on the stud, will engage a suitable socket or depression 41 in the casting into which it will be forced by the resilient construction of the lever.

It will be seen that the casing with the extension plates forms a very convenient handle or gripping means for the eraser, so that it is more conveniently presented for use than in its usual arrangement, and that as worn away the eraser is turned to bring all of its edges for convenient use.

The free end of the cord may be provided with a clamp 45 having a screw 46, that can be readily attached to the frame of a typewriter, or to a convenient portion of a desk. In the normal state, the spring will wind up the cord around the sheave so that the device as a whole is brought to the clamp, and held in such position. When it is desired to use the article, the frame is grasped by the hand and drawn away from its position, for use on the platen, or on the desk, whereby pulling on the cord to unwind it from the sheave, that will put the spring under tension; as soon as the eraser is released, the spring will wind the cord on the sheave back in the casing, that, since the end of the cord is secured on the typewriter or desk, will return the device to the clamp end of the cord, in position for future use.

Having thus described my invention, I claim:

1. The combination with a reel of the class described, comprising a housing, a spring-controlled reel pivotally mounted therein, and a cord attached to said reel, of an eraser mounting comprising an extension to said housing fixedly supporting an eraser receiving stud, and a latch member pivotally attached to said reel housing and adapted to operatively engage said stud.

2. The combination with a reel of the class described comprising a frame, a sheave rev-

oluble in the frame, a cord wound on the sheave to rotate it when drawn off, a spring on the frame connected to the sheave to be put under tension as the cord is drawn off the sheave, and arranged to rewind the cord on the sheave when released, of an extension on said frame, a stud carried by said extension, an eraser mounted on said stud, and means for removably securing the eraser on the stud.

3. The combination with a reel of the class described a frame, a sheave revoluble in the frame, a cord wound on the sheave to rotate it when drawn off, a spring on the frame connected to the sheave to be put under tension as the cord is drawn off the sheave, and arranged to rewind the cord on the sheave when released, of an extension on said frame, a stud carried by said extension, an eraser mounted on said stud, and means for removably securing the eraser on an arm pivoted on the frame to move its free end to and from the stud for engagement therewith, the end of the arm being arranged to engage the stud and retain the eraser on the stud.

4. The combination with a reel of the class described a frame, a sheave revoluble in the frame, a cord wound on the sheave to rotate it when drawn off, a spring on the frame connected to the sheave to be put under tension as the cord is drawn off the sheave, and arranged to rewind the cord on the sheave when released, of an extension on said frame, a stud carried by said extension, an eraser mounted on said stud, and means for removably securing the eraser on an arm pivoted on the frame to move its free end to and from the stud for engagement therewith, the end of the arm being arranged to engage the stud and retain the eraser on the stud, and a lug on the arm, the frame having a socket to be engaged by the lug to retain the arm closed on the eraser.

5. The combination with a reel of the class described a frame, a sheave revoluble in the frame, a cord wound on the sheave to rotate it when drawn off, a spring on the frame connected to the sheave to be put under tension as the cord is drawn off the sheave and arranged to rewind the cord on the sheave when released, said frame comprising a pair of plates, a casing securing the plates offset to form a bearing for the sheave, of an extension on said plates, a stud carried by said extension, an eraser mounted on said stud, and means for removably securing the eraser on the stud.

6. The combination with a reel of the class described a frame, a sheave revoluble in the frame, a cord wound on the sheave to rotate it when drawn off, a spring on the frame connected to the sheave to be put under tension as the cord is drawn off the sheave and arranged to rewind the cord on the sheave

when released, said frame comprising a pair of plates, a casing securing the plates offset to form a bearing for the sheave, of an extension on said plates, a stud carried by said extension, an eraser mounted on said stud, and an arm pivoted on the frame to move its free end to and from the stud for engage-

ment therewith, the end of the arm being arranged to engage the stud to retain the eraser on the stud.

ANTHONY E. YACCARINE.
